Patented July 4, 1916.

UNITED STATES PATENT OFFICE.

ZINA R. ASHBAUGH, OF KANSAS CITY, MISSOURI.

CONVERTIBLE MOLD.

1,189,337.

Specification of Letters Patent.

Patented July 4, 1916.

Application filed June 12, 1915. Serial No. 33,746.

To all whom it may concern:

Be it known that I, ZINA R. ASHBAUGH, a citizen of the United States, residing at Kansas City, in the county of Jackson and State of Missouri, have invented certain new and useful Improvements in Convertible Molds, of which the following is a specification.

My invention relates to improvements in convertible molds in which plastic products such as door frames, silo staves, etc., can be readily cast; and among the objects of the invention are first, the production of a simple and inexpensive mold which can be quickly converted into different forms for molding cement products of various shapes, and second, the production of a mold of such configuration that it can be readily removed from the green products without injury thereto.

Other objects of the invention will hereinafter appear, and in order that said invention may be fully understood, reference will now be made to the accompanying drawing, in which:

Figure 1 is a plan of the mold arranged for the production of cement door frames, Fig. 2 is a cross section on line II—II of Fig. 1. Fig. 3 is a plan of the mold arranged for the production of cement staves and the like. Fig. 4 is a longitudinal section on line IV—IV of Fig. 3, with the division plate removed. Fig. 5 is a cross section on line V—V of Fig. 3. Fig. 6 is a detail of the division plate for use in connection with the mold when converted to the form disclosed by Fig. 3.

In arranging the mold for the door frames, I employ two longitudinal members 1 and 2, and two transverse members 3 and 3^a. The longitudinal member 1 is provided at one end with a centrally disposed hinge member 4 and at its opposite end with a tongue 5 to which a bifurcated handle 6, may be removably connected by a suitable pivot 7. The longitudinal member 2 is provided at one end with a pair of hinge members 8 and at its opposite end with a tongue 9. The outer surface of the tongue 9 is curved and so related to the pivot of the handle 6, that when the latter is adjusted into engagement with said curved surface the abutting ends of the members 2 and 3^a will be firmly locked together. The transverse member 3 is provided at one end with a pair of hinge members 10 and at its op-

posite end with a hinge member 11. The hinge members of the member 3 are pivotally connected to the hinge members of the members 1 and 2 by suitable pivots 12. The transverse member 3^a is provided at one end with a pair of hinge members 13 and at its opposite end with an abutment 14, to which latter the handle 6 may be connected by a pivot 15, as disclosed by Fig. 1. The hinge members 13 are spaced apart to receive the tongue 5, to which they are connected by the pivot 7. The transverse members 3 and 3^a have longitudinal centrally-disposed beads 16 and 17, respectively, to form grooves in the top and bottom of the cement door frames. Said transverse members 3 and 3^a also are provided at their ends with shoulders 18 and 19, respectively, to fit in corresponding notches in the longitudinal members 1 and 2 and thus assist in holding the members 1, 2, 3 and 3^a in proper relation to each other when the mold is closed, as disclosed by Fig. 1. The members 1 and 2 present two opposing, short, intermediate, parallel sides 24 and 25, communicating at their ends with elliptical curved portions 26 and 27, which in turn connect with oppositely-extending, converging sides 28 and 29, communicating with elliptical curved terminals 30 and 31, respectively.

The inner edges of the members 1 and 2 bevel outwardly as indicated at 32 from one end of the short side 24 to one end of the short side 25, and the remainder of said inner edges bevel inwardly as indicated at 33. The bevel portions 32 and 33 are interrupted by a bead 34, extending around the entire length of the inner edges of the members 1 and 2.

The cement door frames may be made either straight or curved and if the latter form is preferred the top of the pallet 22 is curved and the mold is likewise curved, as disclosed by Fig. 2. The curved form of door frame is preferably for silos and other structures having a curved or circular wall.

In the production of cement door frames, the mold is set up as disclosed by Fig. 1 and the cement is poured into the space A until the same is filled, after which the surplus cement is struck off flush with the top of the mold and the surface finished. The cement remains in the mold until it becomes set, after which the core 20 is lifted out of place and the handle 6 is swung out of engagement with the tongue 9. The mold is

then swung open on its hinges and removed from the pallet and the cement door frame resting thereon. When cement staves are to be produced instead of cement door frames the pivots 7 and 12 are taken out and the transverse members 3 and 3^a removed. The two longitudinal members 1 and 2 are then hinged together by passing one of the pivots 12 through the hinge members 4 and 8, respectively, and the handle 6 is removed from the member 3^a and secured to the tongue 5 of member 1 by the pivot 7.

The arrangement of the bevel edges 32 and 33 and the bead 34 results in the production of staves having edges which interlock when placed against each other, and also in the formation of a continuous groove extending around the entire edge of each stave for the reception of cream cement which makes an air and water tight joint between the staves when the same are placed edge to edge.

In order that half staves may be produced in the mold, I provide a division plate 35, which is set in notches in opposite sides of the bead 34, as disclosed by Fig. 3. The underside of the mold is closed by a pallet 22^a.

In practice the mold is laid on the pallet 22^a and then filled with cement which is thoroughly tamped therein, after which the surplus cement is struck off flush with the top of the mold. Handle 6 is then swung

out of engagement with the tongue 9 and the two members 1 and 2 are swung open to clear the cement stave, which is then removed on the pallet 22^a. When the mold is swung open there is no danger of breaking the corners of the green stave as the elliptical curved portions 26, 27, 30 and 31, clear said green stave without injury thereto.

Having thus described my invention, what I claim and desire to secure by Letters Patent, is:

A mold of the character described, consisting of two longitudinal members provided with notches near their ends, a transverse member hinged at its ends to an end of each longitudinal member, a second transverse member hinged at one end to one of the longitudinal members and abutting at its opposite end against the other longitudinal member, shoulders on said transverse members to enter the notches in the longitudinal members, centrally disposed beads extending longitudinally of the inner edges of the transverse members, and a pivoted handle for locking the abutting end of the second transverse member against the longitudinal member.

In testimony whereof I affix my signature, in the presence of two witnesses.

ZINA R. ASHBAUGH.

Witnesses:

F. G. FISCHER,
L. J. FISCHER.
